UNITED STATES PATENT OFFICE.

JAMES E. HELPLING, OF LOS ANGELES, CALIFORNIA.

WINDSHIELD FOR SIDE CARS OF MOTORCYCLES.

1,347,461.

Specification of Letters Patent. Patented July 20, 1920.

Application filed June 11, 1919. Serial No. 303,484.

To all whom it may concern:

Be it known that I, JAMES E. HELPLING, a citizen of the United States, residing at Los Angeles, in the county of Los Angeles 5 and State of California, have invented new and useful Improvements in Windshields for Side Cars of Motorcycles, of which the following is a specification.

My object is to make a wind shield for 10 motor cycle side cars, and my invention consists of the novel features herein shown, described and claimed.

Figure 1 is a top plan view of a motor 15 cycle side car provided with a wind shield embodying the principles of my invention, the view being taken looking in the direction indicated by the arrows 1 in Figs. 2 and 5.

Fig. 2 is a side elevation looking in the 20 direction indicated by the arrows 2 in Figs. 1, 3 and 4.

Fig. 3 is a horizontal cross section on the 25 lines 3—3 of Figs. 2, 4 and 5 and looking in the direction indicated by the arrows.

Fig. 4 is a vertical cross section on the 30 lines 4—4 of Figs. 1, 3 and 5 and looking forwardly as indicated by the arrows.

Fig. 5 is a vertical longitudinal sectional detail on the lines 5—5 of Figs. 1 and 4.

The motor cycle side car 1 has a bottom 35 2 curved forwardly and upwardly and the top 3 extending backwardly from the forward edge of the bottom 2. The attaching plates 4 and 5 are secured to the bottom 2 by rivets, bearing ears 6 and 7 extend upwardly from the attaching plates 4 and 5. Posts 8 and 9 are pivotally connected to the bearing ears 6 and 7 by bolts 10 and 11, and the posts 8 and 9 extend upwardly just be-

hind the rear edge of the top 3. Fittings 12 and 13 are fixed upon the posts 8 and 9 a short distance below the top 3, ears 14 extend forwardly from the fittings 12 and 13, attaching plates 15 are secured against the 45 lower faces of the top 3 by rivets, ears 16 extend downwardly from the attaching plates 15, bearings 17 are pivotally connected to the ears 16 by pins 18, adjusting bars 19 are slidingly mounted through the bearings 17 and connected to the ears 14 by pins 20, and a plurality of ball seats 21 are formed

in the lower faces of the adjusting bars 19. Balls 22 are mounted in the bearings 17 against springs 23 held in place by plugs 24, so that the balls will snap into the ball seats 55 21, and so that by manipulating the adjusting bars 19 the posts 8 and 9 may be tilted forwardly or backwardly.

The bars 19 may be adjusted by forcibly moving the upper parts of the posts 8 and 60 9 forwardly or backwardly to overcome the tensions of the springs 23 and cause the balls 22 to snap from seat to seat 21.

T fittings 25 and 26 are fixed upon the upper ends of the posts 8 and 9 just above 65 the top 3, tubular channel bars 27 and 28 are fixed to the fittings 25 and 26 and extend upwardly to the corners 29 and 30 and have portions 31 and 32 extending forwardly and inwardly to the corner 33. Similar tubular channel bars 34 and 35 are attached to the side outlets of the T's 25 and 26 and extend forwardly and inwardly to the corner 36. A double channel bar 37 fits between the corners 33 and 36. 70 75

The glass plates 38 and 39 fit in the frames thus formed. The bars 34 and 35 are just above the top 3, so that the plates 38 and 39 extend upwardly from near the top 3 to join with the top 3 in protecting the occupants of the side car from the front wind. 80

The wind shield thus constructed is A-shaped in plan and the bar 37 forms the point of the —A— so as to split the head wind and deflect it backwardly and outwardly away from the occupant of the car. 85

Various changes may be made without departing from the spirit of my invention as claimed. 90

I claim:

1. A windshield for a motor cycle side car having a bottom and a front hood, comprising posts pivotally connected to the bottom of the car, adjusting bars pivotally connected to the post and extending forwardly 95 below the front hood of the car, means fixed within the hood for holding the bars in an adjusted position, and a windshield fixed to each post above the hood and extending forwardly, the two shields meeting at an angle 100 forwardly of the posts.

2. A windshield for a motor cycle side car

- having a bottom and a front hood, comprising posts pivotally connected to the bottom, adjusting bars pivotally connected to the posts and extending forwardly below the hood, bearings fixed to the under side of the hood adapted to carry the forwardly extending bars and having means for holding the

bars in an adjusted position, and windshield frames extending from the posts above the hood.

In testimony whereof I have signed my name to this specification.

JAMES E. HELPLING.
